HYDROSTATIC WEIR, GATE, AND THE LIKE

František Jermář, Prague, Czechoslovakia

Application May 5, 1949, Serial No. 91,538
In Czechoslovakia November 29, 1948

6 Claims. (Cl. 61—26)

1

There is a series of hydrostatic weirs or gates of known design using a pair of gate doors hinged on a common horizontal axis and arranged either in a plane or at an angle not much differing from 180°. Weirs or gates of this kind have been designed by Desfontaines.

Weirs of similar design, invented by Chittenden, have been frequently used in the United States.

Both gates are able to make about a quarter of a revolution round a central axis along the sill of the weir. The water pressure from the upper pool acts permanently upon the front side of both gates. The lower gate extends into a concrete chamber of cylindrical shape, which chamber is a common feature of the weirs of the above mentioned design, and by admitting the water to the chamber and allowing thus the pressure from the upper pool to be applied simultaneously to both sides of the lower gate, the water pressure upon the upper gate tends to turn the gates into the horizontal position. By connecting the chamber with the lower water pool, the water pressure acts upon the front side of the lower gate only, which causes both gates to turn into the raised position.

This cylindrical chamber is as a rule filled with water either from the upper or lower pool and causes many difficulties, especially in winter, where freezing of parts, which are in contact with water which is not moving, constitutes a serious drawback of these weirs. Another drawback is the difficult construction of the cylindrical concrete masonry of the chamber, into which the gate must closely fit. If any repairs are made on the lower gate, it is necessary to empty part of the upper pool in front of the gates.

It is an object of the invention to provide weirs or gates acting in a way similar to those of Desfontaines or Chittenden, but which do not require the elaborate cylindrical chamber.

It is a further object of the invention to provide weirs or gates where the above mentioned chamber may be kept permanently empty unless the weir or gates are to be lowered.

A still further object is to permit the use of this chamber in connection with channels to regulate automatically the height of the upper water pool.

A still further object of the invention is to provide a weir or gate where repairs may be made without requiring special arrangements in front of the weir or gate and without applying any substantial forces for raising barriers at this place.

Other advantages and objects of my invention

2

will be apparent from the following specification in conjunction with the accompanying drawing, where Fig. 1 shows a schematic cross section of a movable hydrostatic weir or gate in the raised position, Fig. 2 a cross section of a similar weir in a lowered position, Fig. 3 another embodiment of the invention, using an auxiliary chamber, and Fig. 4 a schematic cross section of a channel with gates arranged in accordance with the invention.

10 The hydrostatic weir as shown in Fig. 1, arranged between vertical side walls 12, comprises an upper gate 1 and a lower gate 2, hinged both on a common horizontal axis 3 on the sill of the masonry 8 of the weir. A shield plate 4 of the 15 shape of a sector of a cylinder having its axis coincident with the axis 3 is joined to the lower end of the gate 2. This shield plate 4 extends into a chamber 7 in the masonry 8 of the weir, said chamber having on its lower front side an 20 abutment 13 along the whole width of the weir and almost contacting the cylindrical shield plate 4 and shutting this chamber from the water of the upper pool. A duct 9 terminating above the 25 normal water level of the upper pool leads to the chamber 7, which is connected with the lower water pool by the duct 10. In the example shown, where the gates act automatically, no valves are provided in the ducts 9 and 10. The cross section of the duct 9 is usually larger than that of the 30 duct 10.

The raised weir is held in its position by the water pressure upon the front side of the lower gate 2, while the chamber 7 is connected with the lower pool and is empty as long as the water level 35 of the lower pool does not rise above the bottom of the chamber 7. The relative height of the gates 1 and 2 are proportioned so that the turning moment upon the lower gate 2 due to hydrostatic pressure from the upper water exceeds the turning moment exerted upon the upper gate 1.

In Fig. 1 the weir is shown in solid lines in the raised position. If water in the upper pool rises above the chosen level, it will enter, by the duct 9 into the chamber 7 and flow to the lower pool 45 through the duct 10. If the duct 10 is unable to lead away all the water supplied by the duct 9, the chamber 7 starts to fill and, when full, the water contained therein starts to build up pressure upon the back of the gate 2. As soon as this 50 pressure rises to such an extent that the turning moment in the clockwise direction exceeds the opposite turning moment upon the front of the gate 2, the gates begin to turn, allowing water to overflow. As soon as the balance between both moments is established, the gates remain in a cer-

tain intermediate position, or, if the amount of water exceeds a certain maximum, the gates take the position 1', 2', 4', shown on Fig. 1 in broken lines.

If the flow of water diminishes, the pressure in the chamber 7 becomes lower and the weir is again raised partly or fully, as the chamber 7 is emptied. The lower gate 2 is sometimes provided with a body 5, increasing its weight and increasing thus the turning moment tending to raise the weir, so as to enable the gate 2 to be of a lesser height with respect to the height of the gate 1 than would otherwise be required. As is shown in Fig. 2, it is possible to form a closed compartment 6 from the lower gate 2, the cylindrical shield plate 4 and the auxiliary wall 11, and to fill this compartment with water either permanently or in accordance with a temporary need. By use of the shield plate 4, it is possible to give to the gates 1 and 2 a shape that is most suitable for the hydraulic conditions, to make the arrangement and maintenance of the hinges simpler and to obtain access to the gates from their back side through the chamber 7, in case the conditions of the gates are to be checked.

The embodiments described with reference to Figs. 1 and 2 are most suitable as crest gates, although they may be used in connection with weirs, water locks, channels and similar structures.

Fig. 3 shows an embodiment primarily suitable for weirs. The arrangement of the gates 1 and 2 with the shield plate 4 and the chamber 7 is similar to that described with reference to Fig. 1. There is however a second auxiliary chamber 14 in front of the chamber 7 and connected with the upper pool by the duct 17. The chamber 14 is provided on the top with one or more cover plates 15 hinged on a horizontal axis 16. The free ends of these cover plates rest against the gates 1 and 2 so as to close the chamber 14 in any position of the gates 1 and 2. In the embodiment according to Fig. 3 this latter result is accomplished by a cylindrical abutment located upon the gates 1 and 2 and having an axis coincident with the axis 3. The cover plates 15 prevent the chamber 14 from being filled with gravel and other solid material carried along by the water. The chamber 14 is under normal conditions connected with the upper pool by the duct 17, which is closed only when maintenance work is to be done on the weir. Ducts 9 and 10 communicate with the chamber 7 and having the same function as previously described. When the weir is raised, the chamber 7 is empty. If the overflowing water covers the entrance to channel 9, the chamber 7 starts to fill and when the channel 10 cannot carry away all the incoming water, the water pressure in the chamber 7 is built up, until it is sufficient to cause the lowering of the gates. The water in the chamber 14 partially flows back to the upper pool through the duct 17. If repairs or maintenance work are to be done on the weir, the cover plates 15 may be raised by means of chains 18' into the upright position 15' shown in broken lines. This raising may be done with a minimum of force as it is accomplished while the pressure of the upper pool is taken up by the gates 1, 2. The cover plates 15 thus constitute a provisional weir.

Fig. 4 shows another embodiment of the invention used as a gate for a channel 19, which may be for instance a by pass channel in a lock, dam or any similar structure. This embodiment includes the upper and lower gates 1 and 2 hinged

on a common horizontal axis with the shield plate 4 joined to the lower gate 2 and extending into the chamber 7. If this channel 19 is to serve as a means for regulating the height of the upper pool, ducts 9 and 10 communicate with the chamber 7, as was described with reference to Fig. 1.

If no automatic regulation of the head of the upper pool is required, the duct 9 in Figs. 1-4 terminates in the upper pool below the water level and is provided with a valve by which the admission of water to the chamber 7 may be controlled. A similar valve is arranged in the channel 10.

As was already mentioned, the gate structure according to the invention may be used in connection with hydrostatic movable weirs, as crest gates, gates for by pass channels, sluice gates and similar structures.

Due to the possibility of shaping the gates to meet local conditions, they are particularly suitable in places where ice conditions are heavy and where ice may be easily carried away over the top of the gate. The gates are not likely to be put out of order by frost, as the essential thereof are either permanently in water or in places where the water enters only when the gates are lowered at high water.

Having now particularly described my invention, and in what manner the same is to be performed, I declare that what I claim is:

1. A hydraulic apparatus to be located between two different water levels, comprising, in combination, a supporting structure having an upper end portion and being formed with a chamber connected to said upper end portion and opening toward the upstream side of the water at the upper level thereof, said chamber having a lower front wall located adjacent to the upstream end of said supporting structure; a lower gate member pivotally connected adjacent the upper end thereof to said upper end portion of said supporting structure and extending from said upper end portion of said supporting structure to a point immediately adjacent to said front wall of said chamber, whereby said lower gate member forms a movable cover for said chamber on the upstream side thereof; an upper gate member forming a continuation of said lower gate member and extending from said lower gate member in a direction away from said front wall of said chamber; and an arcuate shield member connected at one edge thereof to the lower edge of said lower gate member and extending in the downstream direction from said lower gate member so that said shield member is located within said chamber when said lower edge of said lower gate member is located directly over said front wall of said chamber, the said shield member being formed on an arc which has the pivotal connection of said lower gate member as its center, whereby said shield member cooperates with said front wall to substantially seal the chamber from the water on the upstream side thereof when the upper and lower gate members are rotated about said supporting structure by the water flowing from the upper level to the lower level.

2. A hydraulic apparatus to be located between two different water levels, comprising, in combination, a supporting structure having an upper end portion and being formed with a chamber connected to said upper end portion and opening toward the upstream side of the water at the upper level thereof, said chamber having a lower front wall located adjacent to the upstream end of said supporting structure; a lower gate member pivotally connected adjacent the upper end

thereof to said upper end portion of said supporting structure and extending from said upper end portion of said supporting structure to a point immediately adjacent to said front wall of said chamber, whereby said lower gate member forms a movable cover for said chamber on the upstream side thereof; weight means connected to the wall of said lower gate member on the side thereof which confronts the interior of said chamber; an upper gate member forming a continuation of said lower gate member and extending from said lower gate member in a direction away from said front wall of said chamber; and an arcuate shield member connected at one edge thereof to the lower edge of said lower gate member and extending in the downstream direction from said lower gate member so that said shield member is located within said chamber when said lower edge of said lower gate member is located directly over said front wall of said chamber, the said shield member being formed on an arc which has the pivotal connection of said lower gate member as its center, whereby said shield member cooperates with said front wall to substantially seal the chamber from the water on the upstream side thereof when the upper and lower gate members are rotated about said supporting structure by the water flowing from the upper level to the lower level.

3. A hydraulic apparatus to be located between two different water levels, comprising, in combination, a supporting structure having an upper end portion and being formed with a chamber connected to said upper end portion and opening toward the upstream side of the water at the upper level thereof, said chamber having a lower front wall located adjacent to the upstream end of said supporting structure; a lower gate member pivotally connected adjacent the upper end thereof to said upper end portion of said supporting structure and extending from said upper end portion of said supporting structure to a point immediately adjacent to said front wall of said chamber, whereby said lower gate member forms a movable cover for said chamber on the upstream side thereof; an upper gate member forming a continuation of said lower gate member and extending from said lower gate member in a direction away from said front wall of said chamber; first duct means communicating at one end thereof with the interior of said chamber and having the other end thereof located adjacent to the upper water level on the upstream side of said chamber; second duct means communicating at one end thereof with the interior of said chamber and extending from said chamber to the water on the downstream side of said chamber; and an arcuate shield member connected at one edge thereof to the lower edge of said lower gate member and extending in the downstream direction from said lower gate member so that said shield member is located within said chamber when said lower edge of said lower gate member is located directly over said front wall of said chamber, the said shield member being formed on an arc which has the pivotal connection of said lower gate member as its center, whereby said shield member cooperates with said front wall to substantially seal the chamber from the water on the upstream side thereof when the upper and lower gate members are rotated about said supporting structure by the water flowing from the upper level to the lower level.

4. A hydraulic apparatus to be located between

two different water levels, comprising, in combination, a supporting structure having an upper end portion and being formed with a chamber connected to said upper end portion and opening toward the upstream side of the water at the upper level thereof, said chamber having a lower front wall located adjacent to the upstream end of said supporting structure; a lower gate member pivotally connected adjacent the upper end thereof to said upper end portion of said supporting structure and extending from said upper end portion of said supporting structure to a point immediately adjacent to said front wall of said chamber, whereby said lower gate member forms a movable cover for said chamber on the upstream side thereof; weight means connected to the wall of said lower gate member on the side thereof which confronts the interior of said chamber; an upper gate member forming a continuation of said lower gate member and extending from said lower gate member in a direction away from said front wall of said chamber; first duct means communicating at one end thereof with the interior of said chamber and having the other end thereof located adjacent to the upper water level on the upstream side of said chamber; second duct means communicating at one end thereof with the interior of said chamber and extending from said chamber to the water on the downstream side of said chamber; and an arcuate shield member connected at one edge thereof to the lower edge of said lower gate member and extending in the downstream direction from said lower gate member so that said shield member is located within said chamber when said lower edge of said lower gate member is located directly over said front wall of said chamber, the said shield member being formed on an arc which has the pivotal connection of said lower gate member as its center, whereby said shield member cooperates with said front wall to substantially seal the chamber from the water on the upstream side thereof when the upper and lower gate members are rotated about said supporting structure by the water flowing from the upper level to the lower level.

5. A hydraulic apparatus to be located between two different water levels, comprising, in combination, a supporting structure having an upper end portion and being formed with a chamber connected to said upper end portion and opening toward the upstream side of the water at the upper level thereof, said chamber having a lower front wall located adjacent to the upstream end of said supporting structure; a lower gate member pivotally connected adjacent the upper end thereof to said upper end portion of said supporting structure and extending from said upper end portion of said supporting structure to a point immediately adjacent to said front wall of said chamber, whereby said lower gate member forms a movable cover for said chamber on the upstream side thereof; an upper gate member forming a continuation of said lower gate member and extending from said lower gate member in a direction away from said front wall of said chamber; an arcuate shield member connected at one edge thereof to the lower edge of said lower gate member and extending in the downstream direction from said lower gate member so that said shield member is located within said chamber when said lower edge of said lower gate member is located directly over said front wall of said chamber, the said shield member being formed on an arc which has the pivotal connection of said lower gate member as its center, whereby said shield member cooperates with said front wall to substantially seal the chamber from the water on the upstream side thereof when the upper and lower gate members are rotated about said supporting structure by the water flowing from the upper level to the lower level.

6. A hydraulic apparatus to be located between

total connection of said lower gate member as its center, whereby said shield member cooperates with said front wall to substantially seal the chamber from the water on the upstream side thereof when the upper and lower gate members are rotated about said supporting structure by the water flowing from the upper level to the lower level; and a wall member connected at one end to said arcuate shield member and connected at its other end to said lower gate member adjacent said upper end thereof, the said wall being spaced from said lower gate member so as to form with the same and with said arcuate shield member an enclosed space adapted to receive water therein for weighting the gate members.

6. A hydraulic apparatus to be located between two different water levels, comprising, in combination, a supporting structure having an upper end portion and being formed with a chamber connected to said upper end portion and opening toward the upstream side of the water at the upper level thereof, said chamber having a lower front wall; a lower gate member pivotally connected adjacent the upper end thereof to said upper end portion of said supporting structure and extending from said upper end portion of said supporting structure to a point immediately adjacent to said front wall of said chamber, whereby said lower gate member forms a movable cover for said chamber on the upstream side thereof; an upper gate member forming a continuation of said lower gate member and extending from said lower gate member in a direction away from said front wall of said chamber; a second chamber connected to said supporting structure on the upstream side thereof, having a top wall almost contacting one of said gate members adjacent the pivotal connection of said lower gate member, and confronting the upstream side of said lower gate member so as to substantially prevent foreign objects from contacting said lower gate member; a first duct means communicating at one end with said sec-

ond chamber and communicating at its other end with the water on the upstream side of said gate members; a second duct means communicating at one end thereof with said first-mentioned chamber and communicating at the other end thereof with the water on the upstream side of said gate members, the other end of said second duct means being located a substantial distance above the other end of said first duct means; third duct means communicating at one end thereof with said first-mentioned chamber and extending from said first-mentioned chamber to the water on the downstream side of said supporting structure; and an arcuate shield member connected at one end thereof to the lower edge of said lower gate member and extending in the downstream direction from said lower gate member so that said shield member is located within said chamber when said lower edge of said lower gate member is located directly over said front wall of said chamber, the said shield member being formed on an arc which has the pivotal connection of said lower gate member as its center, whereby said shield member cooperates with said front wall to substantially seal the chamber from the water on the upstream side thereof when the upper and lower gate members are rotated about said supporting structure by the water flowing from the upper level to the lower level.
